UNITED STATES PATENT OFFICE.

ZACHARIAH V. PURDY, OF BIRMINGHAM, ALABAMA.

HORSESHOE-MACHINE.

SPECIFICATION forming part of Letters Patent No. 378,111, dated February 21, 1882.

Application filed April 21, 1881. Serial No. 235,674. (No model.)

To all whom it may concern:

Be it known that I, ZACHARIAH V. PURDY, a citizen of the United States, residing at Birmingham, in the county of Jefferson and State 5 of Alabama, have invented certain new and useful Improvements in Horseshoe-Machines, of which the following is a specification, reference being had therein to the accompanying drawings.

10 This invention relates to certain improvements in machines for forming horseshoe-blanks; and it has for its objects to so construct the parts that they can be conveniently adjusted and regulated so as to bring the proper 15 pressure upon any desirable point of the blank during its formation to form blanks of various sizes and weight, as more fully hereinafter set forth. These objects I attain by the means illustrated in the accompanying drawings, in 20 which—

Figure 1 represents a top or plan view of my improved machine complete, with a portion broken away; Fig. 2, a longitudinal vertical sectional view of the same; Fig. 3, a transverse 25 vertical sectional view taken on the line $x-x$ of Fig. 1; Fig. 4, a perspective view of the parts, detached, which bend the bar from which the blank is constructed around the blank-forming die. Fig. 5 represents a view of a portion 30 of the bed of the machine, showing the forming-die, and a portion of the guide and blank-delivering mechanism. Fig. 6 indicates a perspective view of a series of guides or gibs whereby the jaws of the blank-bending arms 35 are guided to bend the blank bar around the forming-die, and Fig. 7 a detail perspective view of one of the parts of the machine.

The letter A indicates the bed of the machine, suitably mounted upon supports B. 40 Midway between the ends of the bed, at opposite sides thereof, are located pillow-blocks C, forming bearings for the journal of the crank-shaft D, which has at one projecting end a driving-wheel, E, by means of which it may be 45 put in motion by a band running from a suitable pulley.

To the crank-shaft are pivoted the pitmen F, which extend in opposite directions and are connected with the traveling cross-heads G, 50 which slide on ways H at opposite sides of the bed of the machine, by means of the adjustable connections H', which are provided with

shanks I, setting in longitudinal recesses at the ends of the pitmen, wherein they are adjustably confined by means of the binding-screws L. The cross-heads, near opposite ends, on the under side are provided with recesses M, in which are pivoted the jaws N, which bend the blank bar around the forming-die. The cross heads at opposite ends are formed 60 with tongues P, which are arranged to slide between the upper and lower guides R, which are adjustably secured to the bed of the machine by means of the screws S. Between said guides are secured the adjustable gibs T, which 65 have their inner edges of such conformation as to force the jaws N against the blank bar and bend it around the forming-die as they are advanced by the pitmen and cross-heads. The jaws N at their forward ends are recessed and 70 provided with anti-friction rollers U, which bear against the inner edges of the gibs as the jaws are advanced toward the forming-die.

The guides R and the interposed gibs are confined between the bed of the machine and 75 the metallic guide-plates V, the said plates being provided with curved cam-grooves X, in which work the friction-rollers Y on the studs Z, in order to open out the jaws and return them to normal position when the traveling cross-heads are drawn back.

The jaws N are beveled on their inner forward edges, as indicated by the letter A', and are provided with cutting-edges B' to cut off a suitable length of the blank bar, which is fed 85 in through grooved guides C' at one side of the machine, the adjustment as to the length of such cut-off portion being regulated by the lower guide-plate R on the opposite side of the machine to that from which the blank bar 90 is fed.

The letter D indicates the forming-dies, which may constitute part of the bed of the machine, or may be formed separately and attached thereto by any suitable means. The configuration of such dies is approximately that of the interior of the horseshoe-blank to be bent around it. The forward edges of the cross-heads are curved, as indicated by the letter E', so as to conform to the contour of the toe of 100 the forming-die, in order to properly shape the toe of the shoe-blank as it is bent around the forming-die.

In the bed of the machine, at each side of

the forming-dies and at their outer edges, are formed converging grooves F' , which have inclined surfaces G' upon which the lifting-fingers H^x ride to raise and deliver the blank, 5 when formed, through delivery-openings in the bed of the machine. These fingers are pivoted to traveling carriages I^2 and are provided with lateral guide-lugs K' , which ride upon the inclined guides L' and direct the fingers in 10 their movement. The carriages are mounted upon wheels which travel upon platforms M' , secured to or forming part of the bed of the machine, and the said carriages are connected to the traveling cross-bars by means of 15 the arms M^2 , pivoted between bearings N' , secured to said cross-heads G .

The operation of my machine is as follows: It will be perceived that it is intended to form a blank at each end of the machine as the 20 bending devices are moved back and forth. The blank bars are fed in through the grooved guides C' at the side of the machine at the proper time, and as the jaws move forward a proper length is cut off by the cutting-edges 25 before mentioned. The forwardly-moving cross-head and the jaws then gradually force the separated portion against the forming-die and bend it around the same as the parts are advanced. When bent upon the return movement of the parts, the pivoted fingers traveling in the grooves at the sides of the forming-die ride up on the inclined bearings therein 30 and lift the blank therefrom and carry it toward the delivery-opening, where it is discharged. By reason of the adjustable connections of the cross-heads by which they are connected to the pitmen it will be apparent that 35 said cross-heads may be so adjusted with respect to the forming-dies as to regulate the thickness of the shoe-blank at will by varying the pressure thereon, and by adjusting the gibs inwardly or outwardly the width of the sides and heels may be also regulated by bringing more or less pressure upon the jaws. 40 The length of the blank bar cut off is regulated by means of the lower guide-bars at the sides of the machine, which, being moved outwardly or inwardly, permit the blank bar to be gaged for a separated portion of greater or 45 less length, as may be desired. In order to cool the metal and the parts of the machine, air-blast pipes may be arranged at each end of the machine, by means of which cold air may be applied to the metal and the parts of the machine for the purpose. 50

The letter K^2 indicates a "flatter," which is secured to the traveling cross-head and extends over the traveling cross-bar, the object of which is to hold the blank down around the 55 forming-die during the bending operation, so as to keep the shoe-blank true during the bending.

In order to relieve the adjustable connections between the pitmen and cross-heads of undue strain, adjustable angle-irons K^3 (see Fig. 7) 65 are fitted to the ends, which take up and bear the strain which would otherwise come upon the same.

Having thus described my invention, what I claim, and desire to secure by Letters Patent, 70 is—

1. The combination, with the traveling cross-heads, the bending-jaws, and the forming dies H^x , of the fingers working in converging grooves at each side of the forming-dies, and the 75 traveling carriage to which said fingers are attached, the grooves having inclined bearing-surfaces upon which the fingers ride to lift and deliver the blanks when finished, substantially as specified. 80

2. The combination, with the bed of the machine, the traveling cross-heads, and the jaws provided with cutting-edges for severing the bar, of the adjustable guides and gibs and the grooved bar-guides whereby the blank 85 bar may be fed to the machine and gaged and cut, substantially as set forth.

3. The combination, with the bed of the machine, the traveling cross-heads, and the forming dies, of the bending-jaws provided with 90 cutting-edges for severing the bars, the adjustable guides and gibs, the grooved bar-guides, the fingers H^x , their carriage, and the inclined guides L' , substantially as described. 95

4. The combination, in a horseshoe-machine, 95 of the traveling cross-heads curved at E' and actuated by a crank, the pitman-rods and their adjustable connections with the said cross-heads, the forming-dies, the bending-jaws pivoted to the cross-heads and provided with cutters and anti-friction rollers, the laterally-adjustable guides and gibs, the fingers H^x and their carriages, and the arms M^2 , pivotally connecting the carriages to bearings on the cross-heads, all substantially as described. 100 105

5. The combination, with the horseshoe-forming dies and their jaws and the traveling cross-heads, of the flatters K^2 , secured to the cross-heads between said jaws, and adapted to operate substantially as described. 110 115

6. The combination, with the cross-heads, the pitman-rods and their connections with said cross-heads, of the angle-irons K^3 , the horseshoe-forming dies and jaws, the guides and gibs, the cam-slotted plates V , and the flatters K^2 , all substantially as described.

In testimony whereof I affix my signature in presence of two witnesses.

ZACHARIAH V. PURDY.
